UNITED STATES PATENT OFFICE.

THOMAS LOUIS KIRBY, OF HARTSVILLE, TENNESSEE

ENGINE ATTACHMENT.

1,214,322.

Specification of Letters Patent. Patented Jan. 30, 1917.

Application filed August 17, 1915. Serial No. 45,938.

To all whom it may concern:

Be it known that I, THOMAS L. KIRBY, a citizen of the United States, and a resident of Hartsville, in the county of Trousdale and State of Tennessee, have invented a new and useful Improvement in Engine Attachments, of which the following is a specification.

My invention is an improvement in engine attachments, and the invention has for its object to provide an attachment for use with internal combustion engines, adapted to be arranged between the carburetor and the intake manifold, and having means for breaking up the particles of unvaporized fuel to form a more volatile gas, more explosive in its nature, and to provide a more thorough and intimate mixture.

A further object of the invention is to provide mechanism for decreasing the fuel consumption without decrease of speed or power, and to provide an attachment which may be applied to stationary as well as to movable engines and motors.

25 A further object is to provide mechanism for admitting at will pure air into the cylinders to be used in cleaning or cooling the cylinders, and in case of motors to act as a brake.

30 A further object is to provide a new and improved form of operating mechanism for the above attachment, for permitting the operator with one foot to adjust the attachment to the required conditions, and to provide a new compact releasable attachment which will be durable because simple in construction and operation.

In the drawings:—Figure 1 is a partial side view of an automobile provided with 40 the attachment and with parts in section, Fig. 2 is an enlarged section on the line 2—2 of Fig. 1, and Fig. 3 is an enlarged sectional view of the attachment and its operating mechanism.

45 The present embodiment of the invention is shown in connection with an engine, not shown, of an automobile 1, the device or attachment being arranged between the carburetor 2 and the intake manifold, not shown, and interposed in the pipe 3, which connects the carburetor with the manifold.

The attachment comprises a casing consisting of a body 4 of tapering form, having a central bore 5, and the small end of the body is externally threaded, and is threaded into a lateral opening 6, in the pipe 3, and

a lock nut 7 is threaded on to the small end to make a fluid tight joint with the pipe.

The upper end of the body is chambered or recessed as indicated at 8, and a cap 9 is 60 threaded on to the said end, the said end being externally threaded for engagement by the cap. The cap has a central opening 10, and a screen 11 is arranged transversely of the opening. A slide valve 12 is mounted to 65 move transversely of the body of the casing in oppositely arranged slots in the side wall and in the chamber or recess 8, the valve moving at the opening of the bore 5 into the chamber.

70 A coil spring 13 is arranged in the chamber between the cap 9 and the valve, and this spring normally acts to hold the valve on its seat. The body is provided with an angular arm 14, extending radially from the body, 75 and the valve has a stem 15, which is mounted to slide between the arms 16 of a fork on the arm.

75 A pin 17 is passed transversely of the arm above the stem to limit the upward movement of the stem, and a coil spring 18 encircles the stem between the arms and the valve, the spring acting normally to hold the valve closed. The valve has an opening 19, which when the valve is in the position shown in Figs. 2 and 3, that is, in normal position, will register with the bore 5 of the body of the casing.

80 A shoulder 20 is formed between the valve and the stem, and this shoulder is adapted to engage the periphery of the body when the valve is closed, that is, when the opening 19 is in register with the bore 5 of the body of the casing.

85 In operation, when the engine is running

90 with the valve in normal position, that is, in the position of Fig. 2, air will enter by way of the screen 11, and the opening 19, and the bore 5 to the pipe 3, and will pass to the cylinders. This position admits the maximum amount of air.

95 If the operator desired to decrease the amount of the air entering he will make traction on the stem 15, against the resistance of the spring 18 in a direction to bring the opening 19 of the valve 100 out of register or partially out of register with the bore 5 and he may control this opening to admit any amount of air between none at all and the full capacity. In descending steep inclines when the engine is 105 coasting with the valve open, air will be drawn into the cylinders to clean and cool

the same, and to act as a brake. Mechanism is also provided for operating the valve and for permitting the operator or driver to control the extent of opening. This mechanism 5 comprises a treadle lever, consisting of portions 21 and 22, extending at approximately a right angle with respect to each other. The portion 21 is curved slightly and is provided with a foot plate 23 at its free end. 10 The portion 22 has a cross head 24 at its free end, and one end of the cross head is pivoted to a bracket 25, which is secured to the under face of the foot board 26 of the automobile in the present instance. The other end of 15 the cross head 24 is connected to the stem 15 of the valve by a flexible member 27, as for instance, a cord or wire.

A coil spring 28 is arranged between the foot board and the portion 22 of the treadle 20 lever, and this spring acts normally to move the treadle lever upward, and the portion 21 of the lever passes through a slot 29, in the foot board to bring the foot plate 23 in position to be engaged by the foot of the operator. 25 The portion 21 of the treadle lever is provided with a laterally extending lug 30, for limiting the upward movement of the lever, and when this lug is in engagement with the under surface of the foot board the 30 valve 12 is in normal position.

Latch mechanism is provided for holding the treadle lever in adjusted position, and for holding the valve in adjusted position. This mechanism comprises a latch lever 31, 35 which is pivoted to the portion 21 of the treadle lever as indicated at 32, and the lever 31 has a foot plate 33, normally in the same plane with the foot plate 23 and in position to be operated by the same foot that operates the treadle lever.

The latch lever has a series of teeth 34, 40 four teeth being provided in the present instance, and these teeth are on that edge of the lever remote from the treadle lever. The 45 teeth are adapted to engage a plate 35, which is secured to the foot plate at the upper end of the opening 29, and a coil spring 36 is arranged between the treadle lever and the inner end of the latch lever, the spring acting 50 normally to hold the teeth 34 in engagement with the plate 35.

It will be evident that when the operator desires to release the treadle lever, he will rock his foot on the plate 23 in a direction to move the plate 33 away from the plate 35. 55 This will compress the spring 36 and will release the teeth 34 from the latch plate 35. A downward movement of the foot will now operate the treadle lever in a direction to open the valve 12. The four teeth give four 60 positions of adjustment and this has been found sufficient in practice.

The improved treadle permits the valve to be opened entirely or partially opened or closed, and by means of the treadle the operator may vary the amount of air passing in accordance with conditions. 65

The spring 13 arranged between the cover and the valve, holds the valve to its seat so that when the valve is closed the air cannot 70 pass through the casing 4. There must be some clearance between the slide valve and the passage in which it moves, so that were it not for the spring 13 there might be some leakage at this point. 75

I claim:—

A valve of the character specified, adapted to be arranged between the carburetor, and the engine to which the carburetor is connected, and comprising a casing having 80 means for engaging the manifold, said casing having a transverse opening near the end remote from the manifold engaging means, a slide valve movable through the slot transversely of the passage of the casing, a spring 85 in connection with the valve for normally holding the valve in register with the passage through the casing, manually controlled means for moving the slide valve in the opposite direction, and a cap covering the outer 90 end of the casing and having an opening provided with a covering of perforate material, said casing being internally enlarged beyond the slide valve, and a coil spring between the valve and the cap for holding the valve to its 95 seat, said casing having a lateral arm provided with an opening for guiding the valve.

THOMAS LOUIS KIRBY.
